CLAIM

The ornamental design for a syringe-type applicator, as shown and described.

DESCRIPTION

FIG. 1 is a top, front and left perspective view of a syringe-type applicator showing our new design;

FIG. 2 is a front elevational view thereof, the rear elevational views being a mirror image thereto;

FIG. 3 is a right side elevational view thereof, the left side elevational views being a mirror image thereto;

FIG. 4 is a top plan view thereof;

FIG. 5 is a bottom view thereof;

FIG. 6 is a top, front and left perspective view thereof, with the shaft shown in retracted position; and,

FIG. 7 is a front elevational view of the applicator as shown in FIG. 6.

The broken line showing of the shaft in FIGS. 1, 2 and 3 is for illustrative purposes only and forms no part of the claimed design.
